UNITED STATES PATENT OFFICE.

FRANK HAETTEL, OF COLUMBUS, OHIO.

MOLDER'S FLASK.

1,135,578.

Specification of Letters Patent. Patented Apr. 13, 1915.

Application filed December 26, 1914. Serial No. 879,080.

To all whom it may concern:

Be it known that I, FRANK HAETTEL, a citizen of the United States, residing at Columbus, in the county of Franklin and State of Ohio, have invented certain new and useful Improvements in Molders' Flasks, of which the following is a specification.

My invention relates to molders' flasks and has particular reference to a peculiarly novel adjustable pin connection between the cope and drag forming such flask.

The main object of my invention resides in the provision of a structure of the type referred to which may be easily adapted for use with hand flasks or machine flasks as the case may be.

Further, my construction is particularly adapted for use upon work requiring a great amount of skill and wherein it is essential that there be no relative shift between the cope and drag itself after the pattern has been removed. It is particularly desirable to prevent this shifting of the cope and drag when a portion of the imprint extends into the cope.

My invention also contemplates a structure wherein the guide pin proper may be removed from each flask as the mold is completed and used upon the succeeding flask. This construction also is such that the guide pin may be adjusted in any desired position with respect to the flask to maintain the two parts in a predetermined position when the pin is in use.

The preferred embodiment of my invention is shown in the accompanying drawings, in which similar characters of reference designate corresponding parts, and in which:

Figure 1 is a view in perspective of a flask showing my invention applied thereto, Fig. 2 is a view in perspective of the cope plate, Fig. 3 is a view in perspective of the drag plate, Fig. 4 is a view in perspective of the guide pin and its co-operating parts, Fig. 5 is a slightly modified type of guide pin, Fig. 6 shows the guide pin structure shown in Fig. 4 in its assembled relation with the cope and drag plates, and Fig. 7 is a similar view showing a modified type of construction of Fig. 5 in assembled relation with the cope and drag plates.

In these drawings, the flask is shown as formed of the usual type, the cope 1 being

shown in superimposed relation with the drag 2. The cope has each end provided with a cope plate of the nature shown at 3, this plate being provided with series of apertures 4, by which the same may be securely attached to the flask and also as having its lower portion provided with an outwardly extending flange 5. This flange 5 is provided with a V-shaped groove 6, this groove and flange forming a pin guide formation.

The drag 2 also has each end provided with a drag plate of the nature shown at 7, this plate being further provided with a series of apertures 8 by means of which it may be attached to the flask. Adjacent its upper edge and in slightly spaced relation thereto are outwardly projecting jaws 9, these jaws being also slightly inclined toward each other and being so formed along their depth dimension to form a seat for the complementally shaped formation 10 carried upon an adjusting belt 11. The lower portion of each of the drag plates is provided with an outwardly projecting stud 12, preferably of polygonal shape in cross section. This stud is designed to snugly fit a similarly shaped aperture 13 formed in the enlarged base portion 14 on the lower part of the triangularly shaped pin 15. This pin is of the shape shown so that it may co-operate with the groove 6 of the cope plate and is further provided with a slot 16 through which the bolt 11 is arranged to pass. The lower end of the rear side of the pin 15 is formed to present a square shoulder, as shown at 17, in order that it may co-operate with a nut 18, this nut and the butterfly nut shown at 19 co-operating to securely lock the pin 15 in any desired position of adjustment on the bolt 11.

As is shown in Figs. 1 and 6, the squared aperture 13 is designed to snugly fit the square stud 12 upon the drag plate so that no relative circular adjustment of the two co-operating parts will be necessary when assembling and in order that the pin may be rigidly held in any position on this stud, the jaws 9 are provided to receive the complementary formation 10 upon one end of the adjusting bolt 11. Because of the polygonal shape of the stud 12, the pin is normally held in an upright position and because of the co-operating nuts 18 and 19, this pin may be rigidly secured in any position of horizontal adjustment so that it may be

adjusted to slidingly engage the groove 6 of the cope plate. A similar structure is also provided on the opposite end of the flask and it will, therefore, be apparent that these pins may be so adjusted as to preclude any possibility of the cope 1 shifting with respect to the drag 2 when the pattern is withdrawn.

After the mold has been completed, it is often desirable to remove all particles that are likely to become broken when the sand is knocked out of the flask after the casting operation. To accomplish this, all that is necessary is to unscrew the butterfly nut 19, slightly move the bolt 11 within its slot 16 in the pin itself, in order that it may be removed from its position of engagement with the jaws 9 on the drag plate and then remove the entire pin structure by withdrawing it from the stud 12. The jaws 9 are in slightly spaced relation with the top of the drag plate, in order that the bolt 11 may be thus slightly elevated to cause its disengagement.

25 A slightly modified type of construction is shown in Figs. 5 and 7. In these figures, the pin 20 is shown as being of triangular form in section, as above and as being used in connection with cope and drag plates as already described, but has its lower end formed as at 21 to seat itself directly between the jaws 9 of the drag plate, thus dispensing with the bolt structure 11 and its coöperating parts. This latter construction may be resorted to where the work is of such class that absolute coincidence between the cope and drag is not essential. This latter construction also permits the more ready removal of the guide pin to be used upon the next flask after the mold has been completed, since it is held in connection with the drag plate only by the seat afforded by the jaws 9.

What I claim, is:

1. A flask guide and pin construction comprising a cope plate, a pin guide formation carried by said plate, a drag plate, a guide pin, and a pair of outwardly projecting jaws on said drag plate, said jaws being inclined toward each other in spaced

relation to form a seat, and means for supporting said pin in an upright position.

2. A flask guide and pin construction comprising a cope plate, a pin guide formation carried by said plate, a drag plate, an outwardly projecting stud on said drag plate, a guide pin the lower portion of which is apertured to fit said stud, jaws on said drag plate, and means arranged to seat itself in said jaws for locking said guide pin in any adjusted position on said stud.

3. A flask guide and pin construction comprising a cope plate, a pin guide formation carried by said plate, a drag plate, and an outwardly projecting stud on said drag plate, a guide pin having a slot therein and having its lower portion apertured to fit said stud, jaws on said drag plate, and an adjusting bolt structure arranged to pass through said slot and formed to seat itself between said jaws for locking said guide pin on said stud.

4. A flask guide and pin construction comprising a cope plate, a pin guide formation carried by said plate, a drag plate, an outwardly projecting stud of polygonal shape in cross section on said drag plate, a guide pin, the lower portion of which is provided with a polygonal aperture to snugly fit said stud, and means for locking said guide pin in any adjusted position on said stud.

5. A flask guide and pin construction comprising a cope plate, a pin guide formation carried by said plate, a drag plate, an outwardly projecting stud of polygonal shape in cross section on said drag plate, a guide pin having a slot therein, outwardly projecting jaws on said drag plate inclined toward each other, an adjusting bolt passing through the slot in said pin, means for locking said pin in any adjusted position on said bolt, and a formation carried by one end of said bolt arranged to seat itself between said jaws.

In testimony whereof I affix my signature in presence of two witnesses.

FRANK HAETTEL.
